J. W. Gibbs, of Albany, N. Y.
assignor to
Rathbone & Co. of same place.
Letters Patent No. 1015, dated June 22, 1858.

The schedule referred to in these Letters Patent and making part of the same.

To all whom it may concern:

Be it known, that J. W. Gibbs in the City of Albany, in the County of Albany, and State of New York, have invented or produced a new and original design for the plates of a six plate stove, and I do hereby declare that the following is a full and exact description of the same, reference being had to the accompanying drawings and to the letters of reference marked thereon.

The accompanying drawings represent the side plate or part of the side plate of a six plate stove, and the ornaments or bracket A running along the upper edge are claimed as original, and also the ornamental figure marked B which forms the center or panel ornament, this ornamental figure, being designed to be placed on all panels, or panels of plates of said six plate stove, and forming the principal ornament or design, of said plate or plates of said six plate stove.

What I claim as my invention and desire to secure by letters patent is the ornamental design and configuration of the plates of a six plate stove, substantially as herein set forth and shown in the annexed drawings.
